UNITED STATES PATENT OFFICE.

CLAUDE F. BRONSON, OF FINDLAY, OHIO.

CHICKEN BROODER.

Application filed December 22, 1924. Serial No. 757,415.

To all whom it may concern:

Be it known that CLAUDE F. BRONSON, a citizen of the United States, residing at Findlay, in the county of Hancock and State 5 of Ohio, has invented certain new and useful Improvements in Chicken Brooders, of which the following is a specification.

This invention relates to chicken brooders and has special reference to an improved 10 water heated chicken brooder.

One important object of the invention is to improve the general construction of brooders of this description.

A second important object of the invention 15 is to provide an improved water heated chicken brooder wherein an electric element is used for heating the water and novel arrangement is made for insuring proper distribution of the heated water.

20 A third important object of the invention is to provide an improved form of chicken brooder wherein special arrangements are made of novel character varying the height between two water compartments, one of 25 which acts as the roof and the other the floor, while keeping these compartments in communication so that water might circulate from one to the other.

With the above and other objects in view 30 as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and

40 Figure 1 is a side elevation of a brooder constructed in accordance with this invention, a part of the curtain used therewith being broken away.

Figure 2 is a section on the line 2—2 of Figure 1.

45 Figure 3 is a fragmentary plan view of the brooder, and Figure 4 is a detail central longitudinal section of one of the flexible tubes for connecting the upper and lower water compartments.

50 In the construction of this brooder there is provided an upper water compartment 10

of conical form and this compartment is provided at its top portion with a filling inlet 11.

Beneath the compartment 10 and spaced 51 below the same is a lower water compartment 12, preferably of cylindrical form and on this lower compartment are carried supporting standards 13 which have threaded upper extremities passing through suitable 56 thimbles 14 at the periphery of the upper compartment, these threaded ends being provided with adjusting nuts 15 so that by rotating these nuts the upper compartment can be moved toward and from the lower compartment, thus regulating the height between the two. Depending from the upper compartment are a plurality of upper convex tube sections 16 and extending upwardly 60 from the lower compartment in alinement 70 therewith are lower tube sections 17, each lower section being connected to a respective upper section by a flexible tube 18 so that the connection of the upper and lower water compartments do not hinder vertical adjustment 75 of one with respect to the other. Depending from the periphery of the upper compartment is a fabric curtain 19, preferably made of flannel and slit at intervals to allow ingress and egress of the chickens. 80 Beneath the lower compartment 12 is located an electric heating element 20 of any preferred form but preferably so designed that when turned on fully the lower compartment is heated to substantially 110° F. The 85 ordinary feed wire 21 leads to this heating element and the flow of current therethrough is controlled by a rheostatic switch 22, the pilot lamp 23 being preferably interposed between the rheostat and the heating element 20. A thermometer 24 may be used in connection with the device, by inserting 90 through a suitable bushing in the upper compartment.

With a construction such as this the water 95 is warmed in the lower compartment and rises through the tubes 16, thus heating the upper compartment by convection, the water flowing downward through certain of these tubes to replace that which rises from the lower compartment. Under these circumstances the upper compartment 100 will be

warmer than the lower, a condition very conducive to health in little chickens since this condition closely approximates the natural hovering of a hen, that is to say, greater warmth above than below. Thus while the chickens are kept from being chilled their feet are not made tender by excessive heat on the floor.

There has thus been provided a simple and efficient device of the kind described and for the purpose specified.

It is obvious that minor changes may be made in the form and construction of the invention without departing from the material spirit thereof. It is not therefore, desired to confine the invention to the exact form herein shown and described, but it is desired to include all such as properly come within the scope claimed.

In the above specification, descriptions and drawings, the invention is described in connection with an electric heating device. The invention is not restricted, however, to such an electric heating device but can be

used in connection with heating devices 25 using liquid and gas fuels of various sorts.

Having thus described the invention, what is claimed as new, is:

A chicken brooder including an upper water compartment forming a brooder roof, 30 a lower water compartment spaced below the upper compartment and forming a brooder floor, means to heat the lower compartment, water circulating connection tubes each having upper and lower terminal portions connected to the upper and lower water compartments, respectively, each of said tubes further having a flexible central portion connecting the respective upper and lower portions, standards carried by the lower water compartment and engaging the upper compartment, and nuts on said standards to adjust the height of the upper compartment above the lower compartment.

In testimony whereof he affixes his signature.

CLAUDE F. BRONSON.
